COMBINATION FISHING ROD HANDLE, WEIGHING SCALE, AND RULE

Gerald H. Dreisbach, North Baltimore, Ohio

Application July 12, 1949, Serial No. 3,845

Term of patent 14 years

(Cl. D31—4)

To all whom it may concern:

Be it known that I, Gerald H. Dreisbach, a citizen of the United States, residing at North Baltimore, in the county of Wood and State of Ohio, have invented a new, original, and ornamental Design for a Combination Fishing Rod Handle, Weighing Scale and Rule, of which the following is a specification, reference being had to the accompanying drawing, forming part thereof;

In the drawing:

Fig. 1 is a plan view of a combination fishing rod handle, weighing scale and rule, showing my new design.

Fig. 2 is a side elevation thereof.

Fig. 3 is an end view as indicated by the arrow 3 in Fig. 2; and

Fig. 4 is a bottom view thereof as indicated by arrow 4 in Fig. 2.

The design of this combination fishing rod handle, weighing scale and rule embraces the

equally spaced indicia on both sides for convenience in measuring length and a weight measuring scale at the top. The grip portion of the handle providing islands spaced on the edge of the handle and surrounded by granulated cork which provides sweat pads for the holding hand.

I claim:

The ornamental design for a combination fishing rod handle, weighing scale, and rule, as shown and described.

GERALD H. DREISBACH.
